UNITED STATES PATENT OFFICE

165,155

POSTER PANEL

Clark H. Hammond, Chicago, Ill., assignor to General Outdoor Advertising Company, Inc.,
Chicago, Ill., a corporation of New Jersey

Application October 6, 1949, Serial No. 5,332

Term of patent 14 years

(Cl. D1—12)

To all whom it may concern:

Be it known that I, Clark H. Hammond, a citizen of the United States, residing at Chicago, county of Cook and State of Illinois, have invented a new, original, and ornamental Design for Poster Panel, of which the following is a specification, reference being had to the accompanying drawing, forming a part thereof, in which:

Fig. 1 is a top plan view of the poster panel showing my new design;

Fig. 2 is a front elevational view thereof;

Fig. 3 is a side elevational view thereof.

I claim:

The ornamental design for a poster panel, as shown.

CLARK H. HAMMOND.
